UNITED STATES PATENT OFFICE.

PAUL LATTA, OF CHICAGO, ILLINOIS.

PHOTOGRAPHIC-PRINTING APPARATUS.

No. 884,740.

Specification of Letters Patent. Patented April 14, 1908.

Application filed October 7, 1907. Serial No. 396,255.

To all whom it may concern:

Be it known that I, PAUL LATTA, subject of the Emperor of Germany, residing at Chicago, in the county of Cook and State of Illinois, have invented certain new and useful Improvements in Photographic-Printing Apparatus, of which the following is a specification.

This invention relates to a photographic-printing apparatus of that kind in which successive sections of a band of sensitized paper are exposed to a negative, the paper during exposure being pressed against the negative.

15 The invention relates more particularly to the means whereby the sensitized paper is pressed against the negative, the object being to press the paper smoothly and evenly thereagainst, in order that a sharp and clear 20 print may be had.

In the accompanying drawings, Figure 1 is a front elevation of the apparatus partly broken away. Fig. 2 is a similar view showing the parts in another position. Fig. 3 is a 25 plan view of the platen.

Referring specifically to the drawings, *a* denotes the supporting frame of the negative plate *b* over which the band of sensitized paper *c* travels. The feed motion of the 30 paper may be effected by any suitable mechanism. Successive sections of the paper are exposed to the light of electric lamps *B* or other illuminating means arranged beneath the negative. The platen for pressing the 35 paper against the negative during exposure comprises a number of sections *d* which are connected by hinges *e*. The platen sections are carried by a vertically sliding frame *k*, having at its ends plates *h* provided with 40 horizontally disposed slots *H* in which work rollers *l* carried on the ends of the outer platen sections. The operation of the frame *k* to press the sensitized paper against the negative by means of the platen sections 45 may be effected by any suitable mechanism, its particular construction not being essential to the present invention. On the back of the platen sections, adjacent to and on both sides of their meeting edges, are secured 50 weights *f*, the purpose of which is to normally hold the sections suspended in a bend below the frame *k* when the latter is in elevated position as shown in Fig. 1.

The operation of the apparatus is as follows:—The paper *c* having been brought into

proper position above the negative *b*, the frame is lowered until the platen sections engage the paper and press it against the negative. The inner sections of the platen press the paper first and as the frame *k* continues to descend, the platen sections gradually straighten out and evenly and uniformly press the paper against the negative. The point of contact moves from the middle of the paper outwardly in opposite directions thus accomplishing the same object as the ends of the fingers do when they are rubbed over the paper. This movement of the platen effectually prevents wrinkling and creasing of the paper and also eliminates air bubbles, all of which are detrimental to a clear and sharp print. During this movement of the platen sections the rollers *l* travel outwardly in the slots *H*. After exposure, the frame *k* is elevated to remove the platen sections from the paper and enable the same to be fed forward for the next print. When the frame is thus elevated, the platen sections drop down and assume their normal position shown in Fig. 1, they being assisted in this by the weights *f*. During this movement of the platen sections, the rollers *l* travel inwardly in the slots *H*.

I claim

1. In a photographic-printing apparatus, a negative holder, a frame movable toward and from the negative holder, and a jointed platen loosely supported at its ends on the frame and slidably endwise thereon, and depending in a bend therefrom.

2. In a photographic-printing apparatus, a negative holder, a frame movable toward and from the negative holder, and having guide slots, a platen comprising hinged sections, and rollers carried by the outer platen sections and mounted in the aforesaid guide slots.

3. In a photographic-printing apparatus, a negative holder, a frame movable toward and from the negative holder and having guide-slots, and a jointed platen supported at its ends in the guide-slots and depending in a bend therefrom.

In testimony whereof I affix my signature, in presence of two witnesses.

PAUL LATTA.
